(57) **CLAIM**

The ornamental design for an air delivery outlet nozzle, as shown and described.

DESCRIPTION

FIG. 1 is a front plan view of an air delivery outlet nozzle showing the new design;

FIG. 2 is a rear plan view thereof;

FIG. 3 is a left side view thereof that is symmetric to the right side view thereof;

FIG. 4 is a top view thereof; and,

FIG. 5 is a bottom view thereof.

That which is depicted in solid lines in the drawings represent the claimed invention and that which is depicted in broken lines forms no part of the claimed invention. The surface formation of a sun logo and of double line lettering for BED-JET in FIG. 4 form no part of the claimed invention.
